UNITED STATES PATENT OFFICE

FRANK J. CURRAN, OF NEW YORK, N. Y., ASSIGNOR, BY MESNE ASSIGNMENTS, TO
STEAM POWER, INC., A CORPORATION OF DELAWARE

BOILER CONSTRUCTION

Application filed March 15, 1927, Serial No. 175,474. Renewed October 10, 1930.

My invention relates to boilers of the so-called flash type, and it has particular relation to the class of flash boilers which are employed in automobiles. The present application is a continuation in part of my co-pending application, Serial Number 654,751, filed July 30, 1923.

One of the objects of the invention is to provide a flash boiler which will supply steam to the engine that is practically free of entrained water, regardless of how suddenly a load may happen to have been applied to the boiler.

Another object of the invention is to provide a boiler in which the disengagement of steam and water is substantially completely effectuated.

A further object of the invention is to provide a throttle control system for super-heated steam, whereby the throttle valve is not exposed to the destructive elevated temperature of super-heated steam.

Another object of the invention is to devise a water drum in which the water is at all times in a state of violent agitation.

It is a further object of this invention to arrange the heating elements of the boiler, whereby the circulation of water therethrough is improved and the possibility of reversal in circulation, due to instantaneous heating, is minimized.

The present invention also has as an object the provision of a novel water drum which requires comparatively little fabrication, and which may be constructed at a material saving in cost over that of the water drums, now commonly employed.

Another object of this invention is to provide a steam coil which is particularly adapted to undergo thermal expansion and contraction without impairing the quality of the joint between the coil and the drum.

These together with other objects will become more apparent from a consideration of the accompanying illustration of an embodiment of a boiler, which may be preferred together with a detailed description of its construction.

The figure is a sectional elevational view

of a boiler embodying the features of my invention.

According to the invention, the boiler includes coils which are arranged to expose their upper portions to a greater amount of heat than the lower portion. In addition, the circulation of the gases among the coils is such as to insure the desired upward flow of the water within the tubes or coils. Accordingly, no difficulty is experienced when a heavy load is placed upon the boiler or when the fire is started suddenly.

Another feature of the present invention, which is likewise aimed to improve the circulation of the water through the tubes, resides in the particular combination and arrangement of the water drum, the steam disengagement drum, and the water return pipe, together with the manner in which the steam and water is discharged in the steam disengagement drum. According to the invention, the water return pipes or downcomers are shielded from direct exposure to the flame or combustion gases. This insures the continued downward movement of the water which is separated in the steam disengagement drum and returned to the water drum by way of the downcomers. Check valves in the downcomers aid in maintaining the desired direction of flow of water in the boiler.

Heretofore, considerable difficulty has been experienced in providing a throttle valve which will withstand, successfully, the elevated temperatures of the super-heated steam passing therethrough. This is due largely to the fact that the throttle valve is opened and closed frequently, while the vehicle is being operated in order to accelerate the same positively or negatively, as the driver may desire. According to this invention, a two-stage super-heater is provided between the stages of which the throttle valve is interposed. The first stage serves to dry the steam thoroughly and impart an initial superheat thereto, whereas the second stage increases the superheat to the extent desired.

The boiler consists of a housing 10, constructed preferably to include a suitable heat insulating material 11. The housing encloses a steam drum 12 located in the upper

portion thereof, a water drum or dome 13, located in the lower portion and a mass of coils and tubes 14 interposed therebetween.

The water drum or chamber consists of two annular adjoining steel pipes 16 and 17 which may be welded together and which are interconnected by small tubes 18 to establish communication therebetween. Feed water is supplied to the water drum through a feed water preheater coil 19 which is disposed adjacent the housing 10, and which discharges the preheated water into the lower steel pipe 16. A burner 21, of any desired construction for example, such as is illustrated in my co-pending application Serial Number 126,305, patented June 18, 1929, Patent No. 1,717,667 is located within and slightly below the annular water drum. The flame from the burner as well as the products of combustion rise and intermingle with a plurality of steam generating coils 22 which interconnect the water drum with the steam disengaging drum. It will be observed that each coil includes a helical construction in which the convolutions are of progressively increasing diameter as they approach the upper drum 12. It will also be observed that the coil is at all points inclined upwardly. Furthermore, the space allowed for the passage of gas is greater among the outer convolutions than among the inner convolutions; this results in greater exposure to heat near the outer portion than near the inner portion of each coil, and assures a more rapid circulation of water through the coils. The steam drum 12 includes a plurality of flues 23 through which the combustion gases pass to a dome portion 24 of the furnace and finally to a discharging passage or chimney 26. For the purpose of providing greater flexibility and elasticity in the coil and also to insure a better and more secure joint between the coil and the steam drum, the upper ends of the individual coils are passed upwardly through the flues of the steam drum and enter the drum from the top.

The end of each coil within the steam drum is curved slightly, in order to discharge the water and steam tangentially and impart a whirling motion thereto. This construction affords a substantially complete separation of steam from water inasmuch as the water tends to accumulate near the perimetrical portion of the steam drum, whereas the steam is withdrawn from the drum through a centrally located tube 27 having a perforated upper end. As the water is discharged from coils 22, it accumulates near the outer portion of the drum and flows into a plurality of downcomers 28 which interconnect the steam drum and the water drum, and which are interposed between the preheater coil and the wall of the boiler. A check valve 29 is connected to the end of each downcomer within the water drum; in order to prevent a re-

versal of flow of the water. Such a reversal in flow would often otherwise result when the downcomer became overheated. The preheater coil 19, which intervenes between the upwardly flowing combustion gases and downcomer pipe functions to protect the downcomer from such exposure to overheating.

The steam which is withdrawn from the steam drum through a perforated pipe is circulated through a super-heater. The super-heater includes two stages, the initial stage of heating being brought about in a coil 30 which is disposed immediately above the steam generating coils 22, and which serves to dry the steam as well as to impart a low degree of superheat thereto, whereas the final stage of heating is effectuated in a second coil 31 disposed within the annulus of the water drum. Between the two super-heater coils, a throttle mechanism 32 is interposed for controlling the flow of steam from the boiler to the engine.

It will be understood, of course, that the invention is not limited to a throttle valve of any particular construction. It will likewise be understood that the check valves 29 employed, may be of any suitable construction such for example as a flap valve.

A boiler constructed according to the principles hereinabove set forth is relatively free from the shortcomings which have characterized flash boilers that have been utilized heretofore. For example, when the consumption of steam is increased suddenly, and it is necessary to accelerate the operation of the burner, comparatively no difficulties are experienced which flow from the entrainment of water in the steam supply. Accordingly, the boiler is very economical from the standpoint of water consumption, a characteristic which is particularly desirable. Furthermore, a reversal in the normal direction of flow of water through the steam generating coils is practically obviated. Another advantage of the boiler resides in the fact that a throttle valve interposed in the manner suggested is not exposed to the destructive action of the highly super-heated steam. Consequently, frequent replacement of throttle valves is unnecessary.

Although I have illustrated and described but a single embodiment of the principles of my invention, it will be apparent to those skilled in the art that the invention is susceptible to many modifications without departing from the spirit thereof, and I desire, therefore, that it be limited to accord only with the prior art in the appended claims.

Having thus described my invention what I claim and desire to secure by Letters Patent is:

1. In a flash boiler, the combination of a water drum consisting of an annular endless tube disposed adjacent a burner; a steam

disengaging drum above the water drum; return water pipes interposed between the water drum and the lower perimetrical portion of the steam drum; a check valve in each of said water pipes; steam generating coils above the burner interconnecting the water drum and the steam drum, the convolutions of the individual coils being of greater diameter as they approach the steam drum; and feed water heating coils interposed between the return water pipes and the steam generating coils.

2. In a flash boiler, the combination of a water drum consisting of an annular endless tube disposed adjacent a burner; a steam disengaging drum above the water drum; return water pipes each provided with a check valve interposed between the water drum and the lower perimetrical portion of the steam drum; steam generating coils above the burner interconnecting the water drum and the steam drum; means for shielding the return water pipes from exposure to the hot boiler gases; and a two-stage superheater consisting of two coils having a throttle valve disposed therebetween.

3. In a flash boiler, the combination of a water drum consisting of an annular endless tube disposed adjacent a burner; a steam disengaging drum above the water drum; return water pipes each provided with a check valve interposed between the water drum and the lower perimetrical portion of the steam drum; steam generating coils above the burner interconnecting the water drum and the steam drum, the convolutions of the individual coils being of greater diameter as they approach the steam drum; feed water heating coils interposed between the return water pipes and the steam generating coils; and a two-stage superheater consisting of two coils having a throttle valve interposed therebetween.

4. In a flash boiler, the combination of a water drum; a steam disengagement drum; water return tubes interconnecting the water drum with the base of the steam drum; steam generating tubes likewise interconnecting the drums, said steam generating tubes being adapted to discharge the steam tangentially within the steam drum; a steam pipe disposed in the mid-portion of the steam drum for withdrawing steam therefrom; and a two-stage superheater connected to said steam pipe having a throttle valve interposed between the stages of the superheater.

5. In a flash boiler, the combination of a water drum; a steam disengagement drum; water return tubes interconnecting the water drum with the lower perimetrical portion of the steam drum; steam generating tubes likewise interconnecting the drums, said generating tubes being adapted to discharge steam tangentially within the steam drum; a steam discharge pipe connected to the mid-portion

of the steam drum; and a superheater connected to said steam discharge pipe, the said superheater including a heating tube for subjecting the steam to an initial superheat; a second superheating tube subjecting the steam to a final superheat; and a throttle valve for controlling the exit of steam disposed between the initial and final superheater tubes.

6. In a flash boiler, the combination of a water drum; a steam disengagement drum; water return tubes interconnecting the water drum with the lower perimetrical portion of the steam drum, each tube being provided with a check valve; steam generating tubes likewise interconnecting the drums, said generating tubes being adapted to discharge steam tangentially within the steam drum; a steam discharge pipe connected to the mid-portion of the steam drum; a multiple-stage superheater connected to the said discharge pipe, said superheater including a heating tube for subjecting the steam to a low initial superheat, and a throttle valve, located at the outside of the boiler so as not to be exposed to the heat thereof, between the initial superheating stage and the next superheating stage for controlling the exit of steam from the boiler.

7. In a flash boiler, the combination of a water drum; a steam disengagement drum; water return tubes interconnecting the water drum with the lower perimetrical portion of the steam drum; steam generating tubes likewise interconnecting the drums, said generating tubes being adapted to discharge steam tangentially within the steam drum; a steam discharge pipe for supplying steam to an engine, said pipe being positioned in the central portion of the steam drum; a feed water heater consisting of coils interposed between the water return tubes and the steam generating tubes; a steam discharge pipe connected to the mid-portion of the steam drum; a multiple stage superheater connected to the said discharge pipe, said superheater including a heating tube for subjecting the steam to a low initial superheat and a throttle valve, located at the outside of the boiler so as not to be exposed to the heat thereof, between the initial superheating stage and the next superheating stage for controlling the exit of steam from the boiler.

8. In a device of the character described, an open fire box; a chamber surrounding the same; a preheating coil mounted to enclose a space above the fire box and communicating with the chamber for delivering water thereinto; a steam dome mounted above the space formed to allow the products of combustion to pass therethrough; a second coil mounted within the said space communicating with the chamber and discharging into the steam dome; means for drawing off steam from the said steam dome; an initial superheater coil connected to the said drawing off

means, said superheater coil being located adjacent the said steam dome; a second superheater coil within the said fire box located so as to be exposed to the heat of the products of combustion before being cooled by contact with other portions of the boiler and a throttle valve located between the said superheating coils but in a position so as not to be exposed to direct heat of combustion gases from the fire box.

9. In a device of the character described, an open fire box, a chamber surrounding the same, a preheating coil mounted to surround a space above the fire box and communicating with the chamber for delivering water thereinto, a steam dome mounted above the space formed to allow the products of combustion to pass therethrough, a second coil mounted within the said space communicating with the chamber and discharging into the steam dome, and a downcomer leading from the steam dome to the chamber outside of the preheating coil which serves as a heat barrier between the fire box and the downcomer.

10. In a device of the character described, an open fire box, a chamber surrounding the same, a preheating coil mounted to enclose the space above the fire box and communicating with the chamber for delivering water thereinto, a steam dome mounted above the space having flue tubes to allow the products of combustion to pass therethrough, a series of coils mounted within the space above the fire box communicating with the chamber passing through the flue tubes and discharging into the steam dome tangentially whereby the steam is forced centerwise, and drain pipes for returning the water from the steam dome to the said chamber.

11. In a device of the character described, an open fire box, a chamber surrounding the same, a preheating coil mounted to enclose the space above the fire box and communicating with the chamber for delivering water thereinto, a steam dome mounted above the said space formed to allow the products of combustion to pass therethrough from said space, a series of coils mounted within the said space and communicating with the chamber and the steam dome, and drain pipes disposed at the outside of the preheating coil for returning the water from the steam dome to the chamber whereby the drain pipes are protected from extreme heat.

12. In a device of the character described, an open fire box, a chamber surrounding the same, a preheating coil mounted to enclose a space above the fire box and communicating with the chamber for delivering water thereinto, a steam dome mounted above the space formed to allow the products of combustion to pass therethrough, a series of coils mounted within the space above the fire box communicating with the chamber and dis-

charging into the steam dome tangentially whereby the steam is forced centerwise, and a superheating coil in the space above the fire box having one perforated end extending into the center of the steam dome for receiving the steam.

13. In a device of the character described, a fire pot water chamber, a steam and water dome, a plurality of steam generating coils communicating with the chamber and the dome, said coils discharging against the sides of the dome for separating the water and steam, and downcomers located in proximity to said sides for leading the separated water to said chamber.

14. In a device of the character described, a fire pot water chamber, a steam and water dome, a plurality of steam generating coils communicating with the chamber and the dome, said coils discharging tangentially against the sides of the dome, for separating the water and steam, downcomers located in proximity to said sides for leading the separated water to said chamber, and means for protecting the downcomers against excessive heat in the fire pot.

15. In a device of the character described, a fire pot water chamber, a steam and water dome, flue passages through the dome, a plurality of steam generating coils communicating with the chamber and the dome and passing upwardly through the flue passages and downwardly into the dome in proximity to the sides of the dome, said coils discharging against the sides, and downcomers located in proximity to the sides for leading the separated water to said chamber.

16. In a flash boiler, the combination of a water drum, a steam disengagement drum, water return tubes interconnecting the water drum with the lower perimetrical portion of the steam drum, steam generating tubes interconnecting the drums, said generating tubes having their ends disposed so as to discharge steam within the steam drum, a steam discharge pipe for supplying steam to an engine, said pipe being positioned in the central portion of the steam drum, and a feed water heater consisting of coils interposed between the water return tubes and the steam generating tubes.

17. In a flash boiler, the combination of a water drum, a steam disengagement drum, water return tubes interconnecting the water drum with the lower perimetrical portion of the steam drum, each tube being provided with a check valve, a feed water preheater coil so disposed as to protect the water in the return pipe from direct exposure to the combustion gases employed for the purpose of generating the steam, steam generating tubes likewise interconnecting the drums, said generating tubes having their ends disposed so as to discharge steam tangentially within

the steam drum, and a steam discharge pipe tapped into the mid-portion of the drum.

18. In a device of the character described, an open fire box, a chamber surrounding the same, a preheating coil mounted to enclose a space above the fire box and communicating with the chamber for delivering water thereto, a steam dome mounted above the space formed to allow the products of combustion to pass therethrough, a plurality of conical coils mounted in overlying relation in the said space communicating with the chamber and discharging into the steam dome, and a downcomer within the fire box leading from the steam dome to the chamber, said downcomer being protected against excessive heat in the fire box by said preheating coil.

19. In a device of the character described, an open fire box, a chamber surrounding the same, a steam dome mounted above the fire box formed to allow the products of combustion to pass therethrough, a plurality of coils in the space between the fire box and steam dome and including a preheating coil surrounding the space between the fire box and the dome and communicating with the chamber to deliver water thereto, and a second coil communicating with the chamber and discharging into the steam dome, and a downcomer leading from the steam dome to the chamber outside of said water preheating coil, said coil protecting the downcomer against excessive heat in the fire box.

20. In a device of the character described, a combustion space, a chamber surrounding the same, a preheating water container in heat conducting relationship to the combustion space and communicating with the chamber for delivering water thereto, a steam dome, a second water container in heat conducting relationship to said space and communicating with said chamber and discharging into the steam dome, and a downcomer protected against the heat of said space by said preheating water container.

In testimony whereof, I affix my signature.
FRANK J. CURRAN.
